(57) **CLAIM**

The ornamental design for a communicator, as shown and described.

DESCRIPTION

FIG. 1 is a front right perspective view of a communicator incorporating our new design.

FIG. 2 is a back right perspective view of the communicator.

FIG. 3 is a front view of the communicator.

FIG. 4 is a back view of the communicator.

FIG. 5 is a top view of the communicator viewed directly from a display portion.

FIG. 6 is a bottom view of the communicator, which is a direct opposite view of FIG. 5.

FIG. 7 is a right side view of the communicator; and,

FIG. 8 is a left side view of the communicator.

The broken lines in the drawings are included for the purpose of illustrating portions of the communicator that form no part of the claimed design.
